UNITED STATES PATENT OFFICE.

SAMUEL WALCOTT BROWN AND WILLIAM HENRY MICHAEL, OF COLORADO SPRINGS, COLORADO, ASSIGNEES OF ONE-THIRD TO JAMES H. BRUCE, OF COLORADO SPRINGS, COLORADO.

ILLUMINATED INDICATOR.

1,106,361.

Specification of Letters Patent. Patented Aug. 11, 1914.

Application filed February 26, 1913. Serial No. 750,789.

To all whom it may concern:

Be it known that we, SAMUEL W. BROWN and WILLIAM H. MICHAEL, citizens of the United States, and residents of Colorado Springs, in the county of El Paso and State of Colorado, have invented a new and Improved Illuminated Indicator, of which the following is a full, clear, and exact description.

10 This invention relates to improvements in illuminated indicators as used on rear ends of vehicles, and has reference more particularly to a device comprising a telescoping casing carrying the indicator, and a lamp associated with the casing for illumination of the indicator.

An object of the invention is to provide an inexpensive, strong, simple, and easily distinguishable, indicator, the casing of 20 which will accommodate indicators of different lengths.

The invention consists of the construction and combination of parts to be more fully described hereinafter and fully set forth in 25 the claim.

Reference is to be had to the accompanying drawing forming a part of this specification, in which like characters indicate corresponding parts in all the views and in 30 which:

Figure 1 is an elevation of an embodiment of my invention; Fig. 2 is a horizontal section on line 2—2, Fig. 1; Fig. 3 is a cross section on line 3—3, Fig. 2; and Fig. 4 is 35 an enlarged sectional view showing the structure by means of which the telescoping portions are bound together.

Referring to the drawings, 5 represents a rectangular member, open at both ends, and 40 having also an open face 6. The face 6 has its opening 7 limited at one end and at the sides thereof by borders forming a part of the face.

The end of the rectangular member 5, 45 where the opening 7 is bordered, is provided with end flanges 8, or any other suitable means, to which the lantern 9 is secured. Engaging the opposite end of the member 5 is a similar rectangular member 10 having 50 one end open, and also an open face 11 similarly provided with an opening 12. The member 10 is of such a size that it engages the member 5 with its open end snugly fitting with its sides 13 and 14 against the 55 sides 15 and 16 of the member 5, and with

its back face 17, and its borders adjacent to the sides 13 and 14, against the back face 18 and the borders adjacent the sides 15 and 16 of member 5.

The member 5, near the end into which the member 10 fits, is provided at the sides 15 and 16 with resilient members 19 and 20. These resilient members are secured in any suitable way to said sides with the free ends disposed near the ends of the member 5. 60 The free ends of the resilient members 19 and 20 are each provided with projections 21 and 22 respectively, each projecting through the sides 15 and 16 of member 5, as shown in Figs. 1 and 4.

The member 10, at its sides 13 and 14, is provided with a series of depressions 23 at a predetermined distance from each other and in alinement with the corresponding projections on the resilient members 19 and 20. The depressions 23, formed in the sides 13 and 14, are so inclined that when the member 10 is forced to telescope into the member 5 the depressed portion of the side will force the projections 21 and 22 up and 70 permit the member 10 to slide into the member 5 until the following depressions register with the projections on the resilient members, which, again, by forcing in, will pass to the following one, etc. But if the member 10 is to be telescoped out of member 5, the projections 21 and 22 will abut against the edge formed in the sides 13 and 14 by the depressions 23 and prevent the sliding of the casing 10 out of the casing 5. The 75 purpose of this will appear hereinafter.

Flexible means 24 are provided at the sides 15 and 16 near the end where the lantern 9 is fixed in the member 5, and also in the sides 13 and 14, near the ends thereof of member 10. The flexible members 24 are positioned near the openings of the open face, so that a ground glass 25, fitting snugly between the sides 13 and 14 of member 10, is forced against the borders of the members 5 and 10 of said flexible members 24. The length of the glass 25 is such that when it abuts against the ends of members 5 and 10, the projections 21 and 22 register with 80 certain depressions 23. Therefore, it can be easily seen that when the glass is positioned in the casing the two members can not telescope toward each other, being limited in this direction by the glass, and cannot telescope out one from the other due to 85 100 105 110

the engagement of the projections 21 and 22 with the depressions 23, as before described.

The ground glass has, preferably, the reference characters, as, for example, the license 5 number and the State, indicated in dead black on the ground surface. The back faces 17 and 18 of the two members 10 and 5 are painted white; and the lantern 9 has, preferably, an opening as wide as the member 10 itself, throwing light through this opening into the members.

The member 5 is preferably made stationary with reference to member 10, and is provided at its lower side 16 with two members 26 to which another indicator can be 15 attached, carrying, for example, the name of the city.

It can be easily seen that with our device when the sides of the glass carrying the 20 reference characters is longer or shorter the casing is, accordingly, reduced in size; that is, if the number of references is one less, the member 10 will telescope into the member 5 to the following depression; and if the 25 number of references are two less, it will telescope the two following depressions; that is, the distance between any of the depressions is substantially equal to a character reference.

30 The device is assembled as follows: The glass 25 is first fitted into the member 10 between the flexible members 24, which press the glass against the borders of the open face. The glass is inserted until it abuts 35 against the closed end of the member 10. The glass is then fitted into the open end of the member 5 with the open end of the member 10 entering the open end of the member 5. The sides 13 and 14 of the open end are 40 provided with depressions 27 in alinement with depressions 23, so that when the casing 10 is forced into the casing 5 the depressions 27, coming in contact with the projections 21 and 22, force the said projections, with 45 the resilient members, away from the sides 13 and 14 and allow the casing to be forced in until the glass 25 abuts against the end portions 28 of the member 5. Simultaneously the projections 21 and 22 register with 50 corresponding depressions 23, so that the

member 10 cannot telescope in or out. To remove member 10 from member 5, the resilient members 19 and 20 must be forced out from the depressions 23.

The reference characters in black on the 55 ground glass, and also the white back of the telescoping case, when illuminated by the lantern 9 through the opening, give a soft illumination without glare or reflection and can be seen from a very long distance. The 60 lamp 9 can be secured or made integral with the member 5 so that the vibration of the moving car will not disturb the connection in any way.

Having thus described our invention, what 65 we claim and desire to secure by Letters Patent is:

A device of the class described comprising a telescopic casing formed of two telescoping members, one of said members having 70 resilient means at the sides thereof; and a projection on each of said resilient means projecting through said sides into said member and said resilient means normally forcing said projection into said casing, the second of said members having depressions in 75 the sides thereof in alinement with said projections and coöperating with the same, each of the depressions having an end wall transverse of the casing length and an inclined 80 bottom, said wall and bottom being so disposed that when the second of said members is forced into the first, the inclined bottom of the depression forces the projection on the resilient member out of the depression 85 and therefore the same does not interfere with the movement of the second member, but if the second member is made to telescope out of the first, the said projection comes into engagement with the wall of the 90 depression and prevents the outward movement of the second member.

In testimony whereof we have signed our names to this specification in the presence of two subscribing witnesses.

SAMUEL WALCOTT BROWN.
WILLIAM HENRY MICHAEL.
